UNITED STATES PATENT OFFICE.

RANKIN E. EUWER, OF NATRONA, PENNSYLVANIA.

COMBINED LETTER-SHEET AND ENVELOP.

1,076,357.

Specification of Letters Patent. Patented Oct. 21, 1913.

Application filed September 30, 1912. Serial No. 723,147.

To all whom it may concern:

Be it known that I, RANKIN E. EUWER, a citizen of the United States, residing at Natrona, in the county of Allegheny, State of Pennsylvania, have invented certain new and useful Improvements in Combined Letter-Sheets and Envelops; and I do hereby declare the following to be a full, clear, and exact description of the invention, such as will enable others skilled in the art to which it appertains to make and use the same.

This invention relates to an improvement in a combined letter-sheet and envelop.

The principal object of this invention is to improve the construction of these devices in such a manner that sufficient room will be provided for tearing the envelop and opening the same without danger of mutilating the letter-sheet.

With these and other objects in view, the invention consists in the construction and novel combination of parts hereinafter fully described, illustrated in the accompanying drawings, and pointed out in the claim hereinafter appended; it being understood that various changes in the form, proportion, size and minor details of construction, within the scope of the claim, may be resorted to without departing from the spirit or sacrificing any of the advantages of the invention.

In the drawing:—Figure 1 is a plan view of the blank from which the combined envelop and letter-sheet is formed, Fig. 2 is a rear view of the envelop showing the letter-sheet folded within the same, the top flap being open; and Fig. 3 is a vertical sectional view taken on the line 3—3 of Fig. 2.

Like reference numerals designate corresponding parts in all the figures of the drawings.

Referring to the drawing, the invention comprises a body portion 5 of the envelop, and extending from opposite ends thereof are end flaps 6—6. Extending from the upper edge thereof is the usual top flap 7. Extending from the edge of the back flap 8 opposite the body 5, is a letter-sheet 9

having side edges 10—10 disposed in spaced relation to the side edges of the back flap 8. The back flap 8 is cut in alinement with the side edges 10 of the letter-sheet, as indicated by 11—11, to form ears 12—12. The letter-sheet 9 can thus be folded on the perforated line 13, and in this manner the folded edge will be disposed below the outer edges 14—14 of the ears 12, and consequently below and in spaced relation from the fold between the body portion 5 and the top flap 7 of the envelop.

In forming the envelop, the rear flap 8 is first folded onto the body portion 5 and the end flap 6 folded and sealed upon the rear flap 8. The letter-sheet 9 is thus disposed outside of the envelop, and after a message has been written thereupon the said letter-sheet can be folded within the envelop on the line 13, as clearly shown in both Figs. 2 and 3 of the drawing. When the envelop is sealed by the closure flap 7, and it is desired to open the same, the envelop can be torn along the upper edge thereof above the letter-sheet. As a result, danger of tearing the letter-sheet while opening the envelop will be eliminated.

What is claimed is:—

The combination with an envelop of a letter sheet integral at one longitudinal edge with the free edge portion of the envelop back and perforated or scored on said integral edge for facilitating folding of said sheet into said envelop, the side edges of said sheet being severed from said back to said integral edge whereby when said sheet is folded into said envelop an oblong longitudinal space exists beyond said integral edge to facilitate tearing the envelop and opening the same without danger of mutilation of said sheet.

In testimony whereof, I affix my signature, in presence of two witnesses.

RANKIN E. EUWER.

Witnesses:

ROBERT M. SKILLEN,
NORA G. EUWER.
